ATTORNEY

UNITED STATES PATENT OFFICE.

GEORGE P. TILTON, OF BOSTON, MASSACHUSETTS.

DESIGN FOR A SPOON OR SIMILAR ARTICLE.

Application filed March 27, 1925. Serial No. 12,909. Term of patent 14 years.

To all whom it may concern:

Be it known that I, GEORGE P. TILTON, a citizen of the United States, residing in Boston, Massachusetts, have invented a new, original, and ornamental Design for a Spoon or Similar Article, which is illustrated in the accompanying drawing, forming part of this application.

Fig. 1 in the drawing is a view of the design in front elevation and Fig. 2 is a view of a cross section taken on the line A—A.

I claim:

The ornamental design for a spoon or similar article as shown.

GEORGE P. TILTON.

Witnesses:

PHILIP E. BRADY,

RICHARD F. CRAWFORD.
